UNITED STATES PATENT OFFICE.

GEORGE H. THACHER, JR., OF ALBANY, NEW YORK, ASSIGNOR TO GEORGE H. THACHER, SR., OF ALBANY, NEW YORK

INCLINED GRATE FOR FURNACES.

1,109,266.

Specification of Letters Patent.

Patented Sept. 1, 1914.

Application filed October 22, 1912. Serial No. 727,148.

To all whom it may concern:

Be it known that I, GEORGE H. THACHER, Jr., a citizen of the United States, residing at Albany, county of Albany, and State of New York, have invented certain new and useful Improvements in Inclined Grates for Furnaces; and I do hereby declare the following to be a full, clear, and exact description of the invention, such as will enable others skilled in the art to which it appertains to make and use the same.

My invention relates to that class of furnace grates, wherein inclined grate surfaces receive their fuel from a central magazine or similar source of supply, and discharge their ashes and clinker into the ash pit, preferably through the intermediary of a dumping grate located at the base of the incline.

Particularly, my invention relates to the inclined grate itself and to the manner in which it is connected at its upper part to the wall of the magazine.

In the accompanying drawing, Figure 1 represents, a top plan view, partly broken away, of my invention, illustrating its application to a suitable form of steam boiler furnace; Fig. 2 represents, partly broken away and partly in section, one of the individual bars of the inclined grate and shows the manner in which the inclined grate bars are supported from the magazine wall at their upper portions and from a supporting bar at their lower portions; Fig. 3 represents a cross-sectional view, partly in elevation, of one of the inclined grate bars; and Fig. 4 represents a top plan view of the upper part of one of the inclined grate bars and Fig. 5 is a perspective view thereof.

Similar letters of reference indicate similar parts throughout the several views.

Referring to the drawing, D indicates the magazine, from which the fine fuel is fed to the upper part of the inclined grate surfaces, which inclined grate surfaces are made up of the individual grate bars I. The fuel is fed from the hopper C and is raised by the conveyer blades e so as to be discharged over the edge of the magazine, as will be understood by those skilled in the art. The inclined grate surfaces preferably discharge upon the dumping grates h n diagrammatically illustrated in Fig. 1. The individual grate bars are provided at their upper ends with a tongue or extension i which enters a corresponding recess j at the upper part of

the corresponding wall of the magazine D, as shown more fully in Fig. 2, sufficient clearance being left for expansion.

As indicated in Figs. 1 and 5, the lower ends of the inclined grate bars rest upon a supporting bar J constituting a part of the frame of the dumping grate. The inclined grate bar I is made up of two side webs with which the tongue or projection i is cast integrally and is likewise joined by cross-connections x, likewise cast integrally therewith. The connections x serve not only to join the two side webs of the inclined grate bar but also serve as anchors for holding in place the individual sections y of the grate surface. These individual sections are preferably provided with a bottom lug z, as shown, which lug has cast within it a wrought iron tongue z', so that, by bending the tongue z' beneath the corresponding cross connection x, it can be held in place, but may be removed by bending the wrought iron tongue in the opposite direction so as to release it from the cross-connection.

It will be particularly noted that the individual sections y are arranged in step order, so as to leave between them spaces indicated at x' in Fig. 5, through which the air issuing from the ash pit enters the fuel. This arrangement is for the purpose of directing the main body of the air thus admitted, into the fuel laterally instead of vertically therein. It will be further noted that the air thus admitted through the openings x' (which extend from side wall to side wall of the inclined grate bar) enters what is substantially a triangular space beneath the descending body of fuel. As a consequence, the pressure of the air is equalized in this space, and the tendency to channel the fuel is correspondingly diminished. So also, the air assists in the down feed of the fuel from one step to the other of the inclined grate-bar, as the fuel is consumed. If desired, the section y may likewise be provided with air openings w', as shown, but these openings are supplemental in their character and can be omitted or may be of any other configuration than the slots indicated.

The principal advantage of supporting the upper end of the inclined grate bars by means of the tongue and slot connection shown is that the distribution of the fuel from the magazine is facilitated for the reason that the air is thus cut off from the

fuel at this point so that the green fuel is partly coked upon contact with the overhanging surface b' of the magazine and upper surface of tongue i . So also, the air 5 being in the main diverted laterally through the slots x' , the danger of channeling is practically avoided, to the great advantage of the operation.

Having thus described my invention what 10 I claim is:

1. The combination with a stationary inclined grate, of a magazine for distributing fuel thereto, said magazine having a slot or groove arranged longitudinally in its outer 15 wall, and the inclined grate having tongues received within and covered by said slot; said tongues being free to move therein when the grate expands with heat substantially as described.

2. The combination with a magazine provided with a slot or groove, of a stationary inclined grate bar provided at its extreme upper end with a flat, inclined tongue adapted to seat within said slot or groove to support the grate bar at its upper end, said tongue being free to move into and out of said slot or groove with the expansion and contraction of said grate bar; substantially 25 as described.

3. A grate bar for inclined grates, having notched and chamfered upper edges and provided with a series of flat, perforate inclined plates seated on said chamfered edges and forming steps, said steps being separate and 35 each removable from its normal position in the grate independently and without movement of any other step, or series of steps each step being provided with a bendable tongue for removably securing it in place; substantially as described.

4. A grate bar for inclined grates, provided with side webs, having notched and

chamfered upper edges cross-connections for said webs formed integral therewith, and individual steps, one for each cross-connection and removably anchored thereto, said steps consisting of flat rectangular plates supported solely at their edges in the chamfers of the web and being spaced apart with the straight front edge of one lying directly above and forming with the straight rear edge of the next an air passage of uniform width from web to web of said bar; substantially as described. 45

5. A grate bar for inclined grates, provided with side webs, cross-connections for said webs formed integrally therewith and inclined individual steps one for each cross-connection and anchored thereto, said steps being independently removable therefrom 50 without disturbing any other step or series of steps, said steps being supported at their edges on said side webs and being spaced apart to form intervening gas openings through said bar of a uniform width from 55 web to web; substantially as described.

6. A grate bar for inclined grates, comprising side webs, cross-connections for said webs, and an inclined tongue integral with said webs and adapted to support the grate 60 bar at its upper end, and inclined steps each anchored to a cross-connection and seated wholly between the top portions of the webs, said steps being independently removable, and the straight front edge of one forming 65 with the straight rear edge of the next an air passage of uniform width, extending from web to web; substantially as described. 70

In testimony whereof I affix my signature, in presence of two witnesses.
